METAL FRAMED WOOD CONTAINER

James E. Wilson, Detroit, Mich., assignor, by direct and mesne assignments, of one-fourth to George C. Knight, Detroit, Mich., and one-fourth to Delos G. Smith

Application September 11, 1944, Serial No. 553,547

8 Claims. (Cl. 217—5)

1

The present invention relates generally to containers. More particularly the invention relates to that type of container which is primarily designed or adapted for use in shipping or transporting articles, such as bottles, and comprises in addition to wooden bottom, side and end walls, a metallic box-like frame structure in the form of a rectangular angle bar lower frame, a rectangular angle bar upper frame, and four angle bar uprights between the corners of the two frames.

One object of the invention is to provide a container of this type which is an improvement upon, and has certain advantages over, previously designed containers and is characterized by the fact that it is extremely rigid and durable and in addition is so designed and constructed that it may be produced or fabricated at a comparatively low cost.

Another object of the invention is to provide a container of the aforementioned type and character in which the metallic frame structure is so designed and constructed that it may be shipped to the user of the container in knocked down form and then readily assembled.

Another object of the invention is to provide a container of the last mentioned character in which the rectangular angle bar lower and upper frames of the frame structure are each of one piece design and have the corner portions thereof connected to the ends of the angle bar uprights by right angle clips, the free ends of which extend through registering or aligned slots in the corner portions of the two frames and the ends of the uprights and are bent inwards into a position wherein they abut against the inner faces of the uprights and are held in place by the end portions of the wooden side walls.

A further object of the invention is to provide a container of the type and character last mentioned in which the lower and upper frames of the frame structure have continuous outstruck ribs which straddle the external portions of the clips and serve to retain or lock the clips against vertical displacement relatively to the frame structure.

A still further object of the invention is to provide a container which is generally of new and improved construction and effectively and efficiently fulfills its intended purpose.

Other objects of the invention and the various advantages and characteristics of the present container will be apparent from a consideration of the following detailed description.

The invention consists in the several novel

2

features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective view of a container embodying the invention;

Figure 2 is a perspective view showing the metallic box-like frame structure of the container before connection or assembly of the various parts thereof;

Figure 3 is a vertical longitudinal section of the container illustrating in detail the manner in which the lower margins of the wooden end walls are interlocked with the end margins of the container bottom wall;

Figure 4 is an enlarged horizontal section of one corner of the container illustrating the manner in which the right angle clips serve fixedly to connect the corner portions of the upper and lower frames to the ends of the uprights;

Figure 5 is another enlarged horizontal section showing the manner in which the clips are inserted into place prior to bending of the ends thereof and mounting of the side and end walls of the container;

Figure 6 is an enlarged vertical section of the upper portion of the container showing the manner in which the inwardly extending flange of the upper frame is bent downwards into interlocked relation with the upper margins of the side and end walls in order to lock such walls against vertical displacement with respect to the frame structure; and

Figure 7 is a perspective of the bottom wall of the container.

The container which is shown in the drawings constitutes the preferred form or embodiment of the invention. It has general capabilities of use although it is primarily designed or adapted for use in shipping or transporting articles, such as bottles. As its component parts the container comprises a metallic box-like frame structure 10, a bottom wall 11, a pair of side walls 12 and a pair of end walls 13.

The frame structure is designed and adapted to be shipped to the user of the container in knocked down form and assembled by the user preparatory to use. It is box-like so far as general contour is concerned and consists of a rectangular angle bar lower frame 14, a rectangular angle bar upper frame 15, and four angle bar uprights 16. The lower frame 14 is formed by

a single strip of stamped sheet metal and embodies an inwardly extending horizontal flange 14^a and an upwardly or vertically extending flange 14^b. As shown in the drawings the flange 14^b is formed integrally with the outer margin of the inwardly extending horizontal flange 14^a. The lower frame 14 is formed by first forming triangular cutouts in the portions of the horizontal flange 14^a that are adjacent the corners of the frame. Thereafter the angle bar strip of which the frame 14 is formed is bent at right angles adjacent each of the triangular cutouts with the exception of the cutouts that are at the ends of the strip. The horizontal flange 14^a of the lower frame 14 is provided with a continuous down struck rib 17 and this is disposed midway between the inner and outer margins of the flange 14^a and serves as a supporting medium for the container as a whole. The vertically extending flange 14^b of the lower rectangular angle bar frame 14 is provided with a continuous outstruck upper rib 18 and a continuous outstruck lower rib 19. The last mentioned ribs are spaced a small distance apart and together with the continuous down struck rib 17 serve to reinforce the lower frame 14. The rectangular angle bar upper frame 15 is the same in size as the lower frame 14 and is disposed directly above the latter. It is formed of a single angle bar type stamped sheet metal strip and embodies an inwardly extending flange 15^a and a vertically extending flange 15^b. The vertically extending flange 15^b is formed integrally with, and depends from, the outer margin of the inwardly extending flange 15^a and is in vertical alignment with the vertically extending flange 14^b of the lower frame 14. The upper frame 15 is formed by first providing triangular cutouts in the portions of the inwardly extending flange 15^a that are disposed adjacent the corners of the upper frame. Thereafter the angle bar type stamped sheet metal strip of which the upper frame is formed is bent at right angles adjacent each of the triangular cutouts with the exception of the cutouts that are at the ends of the strip. As shown in Figure 2, the free ends of the upper frame 15 are disposed diagonally opposite the free ends of the lower frame 14 in order that the frame structure 10 as a whole has maximum strength or rigidity. The vertically extending flange 15^b of the upper frame 15 is provided with a continuous outstruck upper rib 20 and a continuous outstruck lower rib 21. These two ribs are spaced apart a comparatively small distance and serve as a reinforcing medium or instrumentality for the upper frame. The four angle bar uprights 16 are formed of sheet metal stampings and extend between, and serve vertically to space, the lower and upper frames 14 and 15. They are located at the corners of the two frames and consist of flanges 16^a and 16^b. The flanges 16^a of the uprights extend lengthwise of the container and the flanges 16^b extend transversely of the container and are disposed at right angles to the flanges 16^a. The lower ends of the angle bar uprights fit within the corners of the vertically extending flange 14^b of the lower frame 14 and are secured in place by right angle metallic clips 22 and the upper ends of the uprights fit within the corners of the vertically extending flange 15^b of the upper frame 15 and are secured in place by right angle metallic clips 23. The clips 22 extend around the corners of the vertically extending flange 14^b of the lower frame and are provided at the ends thereof with extensions 22^a. The latter extend

through aligned slots 24 in the corners of the vertically extending flange 14^b of the lower frame and the lower ends of the uprights 16 and are bent inwards towards one another so that they fit flatly against the inner faces of the lower ends of the upright flanges as shown in Figure 4. Before the clips are inserted into place the extensions 22^a are arranged in parallel relation as shown in Figure 2. After the clips are shifted into place by inserting the extensions 22^a through the aligned slots 24 the extensions are bent inwards into their operative position with the result that the clips serve rigidly to connect the lower ends of the uprights to the corners of the vertically extending flanges 14^b of the lower frame 14. Preferably the clips are formed of sheet metal stampings. As shown in the drawings, the clips 22 fit between the outstruck ribs 18 and 19 with the result that such ribs hold the clips against vertical displacement with respect to the frame. The clips 23 for connecting the upper ends of the uprights 16 to the corners of the vertically extending flange 15^b of the upper frame 15 are the same in design and construction as the clips 22. They fit around the central portions of the corners of said flange 15^b and embody at the ends thereof extensions 23^a which extend through registering or aligned slots 25 in the corners of the flange 15^b and the upper ends of the uprights 16 and are bent towards one another so that they fit flatly against the inner faces of the upper ends of the flanges of the uprights. Before shifting of the clips 23 into their operative position the extensions 23^a are disposed in parallel relation as shown in Figures 2 and 5 in order that they may pass freely through the aligned slots 25. After shift of the clips 23 into place the extensions 23^a are bent inwards into their operative position by any suitable tool. The exterior of the portions of the clips fit between, and are straddled by, the outstruck ribs 20 and 21 on the vertically extending flange 15^b of the frame 15 and are thus held by such ribs against vertical displacement with respect to the frame. When the frame structure is in its assembled position it is rigid. For purposes of reinforcement each upright flange of each upright is provided with a pair of laterally spaced substantially full length outstruck ribs 16^c. The bottom, side and end walls 11, 12 and 13 are preferably formed of wood and together with the frame structure 10 complete the container. The bottom wall 11 is shaped conformably to, and fits within, the vertically extending flange 14^b of the lower rectangular angle bar frame 14. It rests on the inwardly extending horizontal flange 14^a of said lower frame and has full length upwardly facing grooves 26 along its end margins. The side walls 12 are rectangular and, as shown in Figure 1, are positioned in opposed and spaced apart relation. The bottom edges of the side walls rest on the side margins of the bottom wall 11 and the end margins of said side walls fit within the angle bar uprights 16. The top edges of the side walls are rounded and underlie the side portions of the inwardly extending flange 15^a of the upper frame 15. The lower corners of the side walls are in abutment with the inwardly bent extensions 22^a of the clips 22 and serve to hold the extensions in place. In other words, the lower corners of the side walls are so positioned with respect to the extensions 22^a of the clips 22 that such extensions are locked in place and hence when the container is in its

assembled position the clips 22 are positively held in place. The upper corners of the side walls 12 are in abutment with the inwardly bent extensions 23^a of the clips 23 as shown in Figure 4 and serve when the container is in its fully assembled position positively to lock said extensions 23^a in place and thus prevent withdrawal or removal of the clips 23.

The end walls 13 of the container are rectangular and are of slightly less width than the bottom wall 11. The side margins of the end walls 13 fit against the transversely extending flanges 16^b of the uprights 16 and the bottom margins of said end walls fit within, and are in interlocked relation with, the upwardly facing grooves 26 in the end margins of the bottom wall 11. As a result of the interlocking connection between the bottom margins of the end walls and the end margins of the bottom wall the lower portions of the end walls are held against inward displacement with respect to the frame structure when the container is in its assembled position. The side edges of the end walls 13 are in abutment with the end margins of the side walls 12, as shown in Figure 4, with the result that when the end walls are in place the side walls are locked against inward displacement with respect to the frame structure 10. The top edges of the end walls 13 are rounded and underlie the end portions of the inwardly extending flange 15^a of the upper frame 15.

In order to lock the side and end walls against upward displacement with respect to the frame structure after mounting of such walls in place the inner margin of the inwardly extending flange 15^a of the rectangular angle bar upper frame 15 is bent downwards into interlocked relation with the top edges of the side and end walls as shown in Figure 6. Preferably the inner upper corners of the side and end walls are chamfered or beveled as at 27 and the inner edge portions of the inwardly extending flange 15^a terminate outwards of the inner faces of said side and end walls. By having the inner edge portions of said inwardly extending flange 15^a outwards of the inner faces of the side and end walls a filler of the crossed partition type (not shown) may be slid into place within the container without interference from the flange 15^a of the upper frame 15. If desired the upper portions of the end walls 13 are provided with hand holes 28 in order that the container may be readily gripped in connection with transportation thereof.

In assembling the container the frame structure 10 is assembled as hereinafter described. Thereafter the bottom wall 11 is positioned within the frame structure and manipulated so that the margins thereof rest on the inwardly extending flange 14^a of the rectangular angle bar lower frame 14. After proper positioning of the bottom wall the side walls are shifted into place by positioning the bottom edges on the side margins of the bottom wall and then swinging the side walls outwards so as to bring the end margins thereof into place within the angle bar uprights 16. After shift into place of the side walls the end walls are manipulated into place by inserting the bottom margins thereof into the grooves 26 in the end margins of the bottom wall 11. After insertion of the bottom margins of the end walls into the grooves the end walls are swung outwards so as to bring their side margins against the transversely extending flanges 16^b of the uprights 16. After

mounting or positioning of the side and end walls in place the inner margin of the inwardly extending flange 15^a of the rectangular angle bar upper frame 15 is turned or bent downwards into interlocked relation with the top edges of the side and end walls. This operation completes the container and renders the latter in readiness for use.

The herein described container is essentially simple in design and hence may be manufactured or produced at a comparatively low cost. It is extremely durable because it includes the rigid unitary frame structure 10 and is characterized by the fact that the corners of the side walls serve positively to lock the inwardly bent extensions of the clips in place. The container is further characterized by the fact that the end walls, due to the interlocking connections adjacent their bottom margins, serve when in place to hold the side walls against inward displacement with respect to the frame structure. Because of its specific design and construction the container effectively and efficiently fulfills its intended purpose and is capable of being shipped to the user in knocked down form.

The invention is not to be understood as restricted to the details set forth since these may be modified within the scope of the appended claims without departing from the spirit and scope of the invention.

Having thus described my invention what I claim as new and desire to secure by Letters Patent is:

1. As a new article of manufacture, a container comprising a box-like frame structure in the form of a rectangular angle bar lower frame having an inwardly extending flange and in addition an upwardly extending flange with an outstruck rib therearound, a complementary rectangular upper frame spaced above the lower frame and having a downwardly extending flange with an outstruck rib therearound, a plurality of angle bar uprights adapted to support the frames in spaced relation and having the lower ends thereof fitting within the corner portions of the upwardly extending flange of the lower frame and their upper ends fitting within the corner portions of the downwardly extending flange of the upper frame, a plurality of right angle attaching clamps of substantially the same thickness as the ribs, extending around and fitting against said corner portions, respectively, positioned in side by side and abutting relation with the corner portions of the ribs and having at the ends thereof extensions extending through aligned apertures in said corner portions and the ends of the uprights and bent over for interlocking purposes, a bottom wall disposed within the frame structure and having the margins thereof overlying the inwardly extending flange of the lower frame, a pair of opposed complementary side walls disposed in the frame structure and having the bottom margins thereof positioned in abutment with the side margins of the bottom wall and their end margins fitting within the uprights, and a pair of opposed complementary end walls disposed in said frame structure and having the bottom margins thereof positioned in abutment with the end margins of the bottom wall and their end margins disposed within said uprights, said complementary walls being arranged so that their end margins are in abutting relation and having certain of the corners thereof positioned in abutment with the bent over extensions of the clips and serving positively to lock said extensions in place.

2. As a new article of manufacture, a container comprising a box-like frame structure in the form of a rectangular angle bar lower frame having an inwardly extending flange and in addition an upwardly extending flange with a pair of spaced apart outstruck ribs therearound, a complementary rectangular angle bar upper frame spaced above the lower frame and embodying a downwardly extending flange with a pair of spaced apart outstruck ribs therearound, a plurality of angle bar uprights adapted to support the frames in spaced relation and having the lower ends thereof fitting within the corner portions of the upwardly extending flange of the lower frame and their upper ends fitting within the corner portions of the downwardly extending flange of the upper frame, and a plurality of right angle clips of substantially the same thickness as the ribs, extending around and fitting against said corner portions, respectively, interposed between and in interlocked relation with the ribs, and having at the ends thereof extensions extending through aligned apertures in said corner portions and the ends of the uprights and bent inwards into abutment with the inner surfaces of the upright ends for interlocking purposes, a bottom wall disposed within the frame structure and having the margins thereof overlying the inwardly extending flange of the lower frame, a pair of opposed complementary side walls disposed in the frame structure and having the bottom margins thereof positioned in abutment with the side margins of the bottom wall and their end margins fitting within the uprights, and a pair of opposed complementary end walls disposed in said frame structure and having the bottom margins thereof positioned in abutment with the end margins of the bottom wall and their end margins fitting within the uprights, said complementary walls being arranged so that their end margins are in abutting relation and having certain of the corners thereof positioned in abutment with the bent over extensions of the clips and serving positively to lock said extensions in place.

3. As a new article of manufacture a container comprising a box-like frame structure in the form of a rectangular angle bar lower frame with an inwardly extending flange and an upwardly extending flange, a complementary rectangular upper frame spaced above the lower frame and embodying a downwardly extending flange, a plurality of angle bar uprights adapted to support the frames in spaced relation and having the lower ends thereof positioned in abutment with the corner portions of the upwardly extending flange of the lower frame and their upper ends positioned in abutment with the lower corner portions of the downwardly extending flange of the upper frame, and a plurality of right angle clips extending around and associated with said corner portions, respectively, and having at the ends thereof extensions extending through aligned apertures in said corner portions and the ends of the uprights and bent over for interlocking purposes, a bottom wall disposed within the frame structure and having the margins thereof overlying the inwardly extending flange of the lower frame, a pair of opposed complementary side walls disposed in the frame structure and having the bottom margins thereof positioned in abutment with the side margins of the bottom wall and their end margins fitting within the uprights, and a pair of opposed complementary end walls disposed in said frame structure and having the bottom margins thereof positioned in abutment with the end margins of the bottom wall and their end margins fitting within the uprights, and a pair of opposed complementary

bottom margins thereof positioned in abutment with the end margins of the bottom wall and their end margins fitting within the uprights, said complementary walls being arranged so that their end margins are in abutting relation and having certain of the corners thereof positioned in abutment with the bent over extensions of the clips and serving positively to lock said extensions in place.

4. As a new article of manufacture, a container comprising a box-like frame structure in the form of a rectangular angle bar lower frame with an inwardly extending flange and an upwardly extending flange, a complementary rectangular upper frame spaced above the lower frame and embodying a downwardly extending flange, a plurality of angle bar uprights adapted to support the frames in spaced relation and having the lower ends thereof fitting within the corner portions of the upwardly extending flanges of the lower frame and their upper ends fitting within the corner portions of the downwardly extending flange of the upper frame, and a plurality of right angle clips extending around and fitting against said corner portions, respectively, and having at the ends thereof extensions extending through aligned apertures in said corner portions and the ends of the uprights and bent inwards into abutment with the inner faces of said ends of the uprights, a bottom wall disposed within the frame structure and having the margins thereof resting upon the inwardly extending flange of the lower frame, a pair of opposed complementary side walls disposed in the frame structure and having the bottom margins thereof positioned in abutment with the side margins of the bottom wall, their end margins fitting within the uprights, and their corners arranged in abutment with the inwardly bent extensions of the clips and serving to lock said extensions in place, and a pair of opposed complementary end walls disposed in said frame structure and having the bottom margins thereof positioned in abutment with the end margins of the bottom wall and their end edges in abutment with said end margins of the side walls.

5. As a new article of manufacture a container comprising a box-like frame structure in the form of a rectangular angle bar lower frame with an inwardly extending flange and an upwardly extending flange, a complementary rectangular angle bar frame structure spaced above the lower frame and embodying an inwardly extending flange and a downwardly extending flange, a plurality of angle bar uprights adapted to support the frames in spaced relation and having the lower ends thereof positioned in abutment with the corner portions of the upwardly extending flange of the lower frame and the upper ends positioned in abutment with the lower corner portions of the downwardly extending flange of the upper frame, and a plurality of right angle clips extending around and associated with said corner portions, respectively, and having at the ends thereof extensions extending inwards through aligned apertures in said corner portions and the ends of the uprights and bent over for interlocking purposes, a bottom wall disposed within the frame structure and having the margins thereof overlying the inwardly extending flange of the lower frame, a pair of opposed complementary side walls disposed in the frame structure and having the bottom margins thereof positioned in abutment with the side margins of the bottom wall and their end margins fitting within the uprights, and a pair of opposed complementary

end walls disposed in said frame structure and having the bottom margins thereof positioned in abutment with the end margins of the bottom wall and their end margins disposed adjacent the uprights, said complementary walls being arranged so that their end margins are in abutting relation and having certain of the corners thereof positioned in abutment with the bent over extensions of the clips and serving positively to lock said extensions in place, the inner portions of the inwardly extending flange of the upper frame extending over and around the top edges of said side and end walls and serving to hold said side and end walls against upward displacement with respect to the frame structure and also to hold the upper portions of said side and end walls against inward displacement.

6. As a new article of manufacture a container comprising a box-like frame structure in the form of a rectangular angle bar lower frame with an inwardly extending flange and an upwardly extending flange, a complementary rectangular angle bar frame structure spaced above the lower frame and embodying an inwardly extending flange and a downwardly extending flange, a plurality of angle bar uprights adapted to support the frames in spaced relation and having the lower ends thereof positioned in abutment with the corner portions of the upwardly extending flange of the lower frame and the upper ends positioned in abutment with the lower corner portions of the downwardly extending flange of the upper frame, and a plurality of right angle clips extending around and associated with said corner portions, respectively, and having at the ends thereof extensions extending inwards through aligned apertures in said corner portions and the ends of the uprights and bent over for interlocking purposes, a bottom wall disposed within the frame structure and having the margins thereof overlying the inwardly extending flange of the lower frame, a pair of opposed complementary side walls disposed in the frame structure having the bottom edges thereof resting on the side margins of the bottom wall, their end margins fitting within the uprights and their corners arranged in abutment with the extensions of the clips and serving to lock said extensions in place, and a pair of opposed complementary end walls disposed in said frame structure, having the end edges thereof fitting within the uprights and flatly against the end margins of the side walls, and also having their bottom margins fitting in, and in interlocked relation with, grooves in the end margins of the bottom wall whereby their lower portions are held against inward displacement relatively to the frame structure, the inner portions of the inwardly extending flange of the upper frame being extended over and around the upper edges of the side and end walls and serving to hold said side and end walls against upward displacement and also to hold the upper portions of said end walls against inward displacement.

7. A box-like frame structure adapted with bottom, side and end walls to form a container and comprising a rectangular angle bar lower frame embodying an inwardly extending flange and an upwardly extending flange, formed of a

single strip of stamped sheet metal, and having the ends thereof terminating at one of its corners, a complementary rectangular angle bar upper frame spaced above the lower frame, embodying an inwardly extending flange and a downwardly extending flange, formed of a single strip of stamped sheet metal, and having its ends terminating adjacent one of its corners and disposed diagonally opposite the ends of the lower frame, a plurality of angle bar stamped sheet metal uprights adapted to support the frames in spaced relation and having the lower ends thereof fitting within the corner portions of the upwardly extending flange of the lower frame and their upper ends fitting within the corner portions of the downwardly extending flange of the upper frame, and a plurality of right angle clips extending around and fitting against said corner portions, respectively, and having at the ends thereof extensions extending through aligned apertures in said corner portions and the ends of the uprights and bent over for interlocking purposes.

8. As a new article of manufacture, a container comprising a box-like frame structure in the form of a rectangular angle bar lower frame having an inwardly extending flange and in addition an upwardly extending flange with a pair of outstruck parallel ribs extending therearound, a complementary rectangular upper frame spaced above the lower frame and having a downwardly extending flange with a pair of outstruck parallel ribs extending therearound, a plurality of angle bar uprights adapted to support the frames in spaced relation and having the lower ends thereof fitting within the corner portions of the upwardly extending flange of the lower frame and their upper ends fitting within the corner portions of the downwardly extending flange of the upper frame, a plurality of right angle attaching clips extending around and fitting against said corner portions, respectively, positioned in side by side and abutting relation with the corner portions of the ribs and having at the ends thereof extensions extending through aligned apertures in said corner portions and the ends of the uprights and bent over for interlocking purposes, a bottom wall disposed within the frame structure and having the margins thereof overlying the inwardly extending flange of the lower frame, a pair of opposed complementary side walls disposed in the frame structure and having the bottom margins thereof positioned in abutment with the side margins of the bottom wall and their end margins fitting within the uprights, and a pair of opposed complementary end walls disposed in said frame structure and having the bottom margins thereof positioned in abutment with the end margins of the bottom wall and their end margins disposed within said uprights, said complementary walls being arranged so that their end margins are in abutting relation and having certain of the corners thereof positioned in abutment with the bent over extensions of the clips and serving positively to lock said extensions in place.

JAMES E. WILSON.
